UNITED STATES PATENT OFFICE.

THOMAS L. CONDER, OF COLUMBIA, SOUTH CAROLINA, ASSIGNOR OF FORTY-NINE ONE-HUNDREDTHS TO ARTHUR W. HAMBY, OF COLUMBIA, SOUTH CAROLINA.

STORE SERVICE.

Application filed February 19, 1925. Serial No. 10,260.

This invention relates to an improvement in stores, particularly those engaged in vending such commodities as groceries, wherein it has been found possible to do an increased business with a minimum of overhead, by the use of a systematic arrangement.

At the present time, the management of stores operated on a self service plan is very seriously concerned with the damage and theft occasioned through handling of the goods by customers. This undesirable feature is overcome in the present invention, which requires clerks to attend to customers' wants and at the same time provides for a very adequate display.

It has always been noticeable, and particularly so in grocery stores, that a customer often has to carry a basket full of merchandise about the store. To eliminate this and make the customer as comfortable as possible, and likewise to speed up transactions, this invention utilizes a conveyor system which is of a very simple character, providing also for the return of the empty carriers to a suitable receptacle for re-use.

By reason of the location and character of business, it is frequently necessary to employ an arrangement whereby two distinct groups of customers may be cared for at the same time. The invention is easily applied for this purpose and the display and storage structure for the goods has been found to be quite efficient.

Referring to the drawings:

Figure 1 is a top plan view of the store embodying the present invention.

Figure 2 is a longitudinal section on line 2-2 of Figure 1.

Figure 3 is a section on the line 3-3 of Figure 1.

Figure 4 is a view in transverse section of one of the shelf sections.

Figure 5 is a view showing a carrier handle with a pulley mechanism secured thereto and engaging a cable.

Figure 6 is a view of a trip mechanism employed at one end of a return cable.

In the drawings, I have illustrated a store comprising side walls 10 and 11. The front of the store is provided with vestibules 12, between which is arranged a suitable show case 13. The vestibules are provided with entrances and exits having gates 14 and 15 arranged to swing in opposite directions so that the customers will enter by one of the

gates 14 and will leave by the adjacent gate 15.

A partition 16 is arranged at the rear of the store and is provided with suitable gates 17 leading into a supply room 18. These gates may be provided with locks to prevent anyone but authorized persons from gaining entrance to the supply chamber.

Arranged centrally of the store is a series of parallel shelves 19 or suitable supporting means for articles of merchandise. Upon reference to Figure 1 it will be seen that the shelves 19 consist of sections 20 and 21 arranged at right angles to each other, the apices of the angles extending toward the front of the store. These shelves are divided vertically by a partition 22, as shown in Figure 4, so that the shelves are formed into front and rear portions 23 and 24 for a purpose which will be presently described. At this point, however, it may be stated that the portion 23 constitutes the display section while the portion 24 is designed to receive the staple articles and any other stock for which there is no need of display.

The angular and parallel arrangement of the shelving permits of an economical utilization of store space without in the least detracting from the value of the shelves as a means of display or for stock purposes. Further, it is possible for the clerks to move about the shelving quickly and easily so that the service will be rapid.

On opposite sides of the shelving are arranged counters 25 which extend from a point adjacent the front of the store toward the rear where they are joined by a transverse counter 26 having hinged upwardly, swinging gates 27 thereon. At the front of the store, the counters 25 each terminate adjacent a bin or receptacle 28 which are conveniently arranged in the vestibules and contain a suitable supply of carriers, as will be presently described. It will be observed that the shelves 21 and 22 are arranged at an acute angle to the counters so that customers passing along the counters will readily see any goods displayed in the external sections 23 of said shelving.

By reason of the angular disposition of the shelves to each other and to the counters as just described, it will be clear that a display of luxuries, new delicacies or specials may be easily seen by patrons when placed in the external sections 23 of the shelves. Articles

of a staple nature will be disposed in the rear portions 24 of the shelving, as a customer will usually call for this type of merchandise and there is generally no need for 5 its display.

It will be understood that clerks are stationed behind the counters at suitable intervals, who attend the customers' wants, so that handling of the goods by customers, and 10 possible theft, is eliminated while at the same time the transaction is speeded up.

The spaces between the counters 25 and the walls of the store are divided by a partition 29 forming two aisles or passageways 30 and 15 31, respectively. Since the aisle structure and associated parts is the same on both sides of the store, only one will be described.

The aisle 30, adjacent the counter 25, is closed at its entrance end by a turn-stile 32 20 which may be turned in one direction only, that is, to permit a customer to enter the aisle 30. The customer after entering the aisle 30 will pass along the counter toward the rear of the store, purchasing articles of 25 the clerks, and must pass a cashier's station 33. The customer then leaves the store through the aisle 31, but, if for any reason it is desired to delay, benches 34 are arranged adjacent the walls of the store for the convenience 30 and comfort of the patrons.

In order to facilitate the customer's passage through the store and to eliminate the necessity of the customer carrying a basket full of heavy merchandise, cables 35 are supported upon the counters 25 by means of suitable standards 36. These cables are arranged at a suitable distance above the counter both with relation to the customer and to the clerks who are behind the counter so as to be within 40 in convenient reach. Referring to Figure 1, the bins or receptacles 28 are adapted to contain baskets or other carriers 37, the handles of which are provided with suitable pulleys 38, as shown in Figure 5. The pulleys 38 are of a type readily attachable and removable from the cables 35.

Thus, a customer enters the store, takes a basket from one of the bins and places it on the cable 35 and has merely to push the basket 50 over the cable each time travel is resumed along the aisle 30 to the cashier's station. Since the present invention requires that clerks be stationed at suitable intervals behind the counter, obviously, the passage of a 55 customer through the store is considerably speeded up by reason of this conveyor structure.

Furthermore, one customer may readily pass another in the aisle 30 by detaching the 60 carrier from the cable and replacing it at a desired point in advance or in rear of the intermediate purchaser.

As has been previously referred to, the cashier's station is arranged at the rear of 65 the store and it will be quite clear that after

having made the desired purchases, and being at the end of the aisle 30, a customer must pass the cashier. The cable 35 extends to a point adjacent the cashier's desk and when the customer reaches this point the cashier 70 merely removes the basket, empties the contents, and computes the cost of the purchases. The customer then gathers up the merchandise and leaves the store by the aisle 31, adjacent the side wall. 75

Arranged to extend above the cable 35 and from a point adjacent the cashier's desk to each of the bins, is a second cable 39. This cable is supported at the rear by the partition 16 and is inclined toward the front of the 80 store, terminating over the bin 28. At its end adjacent the bin the cable is supported by a standard 40 and is provided with a trip mechanism 41. This trip mechanism consists merely of rolling over the end of the cable 39, 85 as at 42. Thus, the cashier takes the empty baskets, places them on the inclined cable and by slight initial pressure they are caused to roll, by gravity, down the cable, and by means of the trip mechanism, ultimately drop 90 into the bin so that a fresh supply of carriers will always be available.

It will be readily understood that in some cases, as for example, in a relatively narrow store, that the double structure disclosed will 95 not be possible of application. In such event, only one section of parallel shelves will be employed and similarly a single counter and carrier mechanism. It will be seen that I have provided an improvement in stores 100 which is capable of a ready and efficient application, at the same time being of such a nature as to speed up the transactions without being the least complicated or distasteful to either the customer or store attendants. 105

I claim:

1. In a store, pairs of parallel entrance and exit aisles extending on each side of the store, a receptacle station at the forward end of each entrance aisle and extending toward the 110 interior of the store, a cashier's station between the rear ends of said aisles, the central part of the store between said aisles, cashier's and receptacle stations being occupied by a series of independent parallel V-shaped shelves, counters between said shelves and the adjacent entrance aisles, a conveyor system mounted on said counters whereby receptacles may be manually propelled above the 115 counters from the entrance to the cashier's desk and returned by gravity to the receptacle 120 station.

2. In a store, a pair of entrance and exit aisles arranged upon opposite sides thereof, gates at the entrance to the store permitting entrance through the entrance aisles and exit through the exit aisles, the front of the store 125 between said gates providing space for a show case, and for bins in the rear of said show case for containing carrying baskets, said bins be- 130

ing arranged adjacent the entrance aisles upon opposite sides of the store, a plurality of parallel angular shelves arranged in alignment and extending from front to rear of the 5 store, counters extending from front to rear of the store on opposite sides of said shelves and forming with said bins and show case an enclosure for the shelves, the said counters being arranged adjacent the entrance aisles and 10 the shelves being arranged at an angle to said counters whereby goods are visible from said aisles upon opposite sides of the store, a cashier's station at the rear of the store in direct communication with said entrance aisles and forming an enclosure with said counters for 15 said shelves at the rear of the store, a conveyor system mounted upon said counters and extending from the basket bins to the cashier's station, said system comprising a track upon which a purchaser may place a basket from 20 one of the bins and move it as he passes along the counter to immediately adjacent the cashier's station, and a second track whereby the cashier may return an empty basket by gravity to either of said bins. 25

In testimony whereof I have hereunto set my hand.

THOMAS L. CONDER.
